UNITED STATES PATENT OFFICE

LUDWIG A. OLSEN, OF BROOKLYN, NEW YORK

POLISHER

Application filed May 26, 1931. Serial No. 540,076.

This invention relates to a device for polishing, and particularly to a device adapted simultaneously to apply a polish to one portion of a surface and to rub or buff an adjacent portion of the surface, whereby the polishing operation may be continued and the polish may be applied and rubbed to the desired polished condition in a single operation.

In recent years, numerous mechanical devices for polishing surfaces such as floors and the like have been suggested, and many of them placed upon the market. The use of such devices has resulted in great labor saving in so far as the rubbing of the floor after application of the polish is concerned. So far as I am aware, no device has heretofore been known which is capable satisfactorily of applying the polishing material and rubbing it to develop the desired polish on the surface, both in a single operation. I am aware that various devices have been tried for this purpose, in which spreaders for the wax or the polish are attached to the rubbing or brushing device, and precede it over the surface. With such devices, however, any excess polish, or any polish which is loose upon the surface is likely to be caught by the rotating brush and thrown by centrifugal force against walls or furniture, or onto nearby rugs, and this spattering over adjacent objects may, in many cases, prove seriously objectionable. Furthermore, in any device in which the polish is applied to a place outside of the brush and is then polished, any polish which remains soft or gummy is likely to collect on the bristles of the brush, and thereby to prevent the production of a satisfactory finish upon the floor or other surface.

Accordingly, it is an object of my invention to provide a device which will be adapted to apply the polishing material in such manner that it will be completely utilized in polishing the surface, and all splattering or wastage of the material and gumming of the polisher, with consequent streaking etc., will be substantially avoided.

In the accompanying drawing I have illustrated by way of example a preferred form

of my invention and a number of modifications thereof.

Fig. 1 is a side elevation of a preferred embodiment of my invention partly in section.

Figs. 2 and 3 are respectively horizontal and vertical fragmentary section views illustrating another modification within the invention.

Referring first to Fig. 1, I have illustrated a polisher having an annular brush 10 rotatably mounted with a housing 11. This brush is driven by the motor 12 through the gear 13 on the motor shaft 14, the idler gear 15, and the ring gear 16 attached to the back of the brush 10. Above the housing 11 and surrounding the motor 12 is a second housing 17, the upper portion of which forms an annular reservoir having a filler opening 18 and a valve outlet 19. Beneath this reservoir, or otherwise adjacent this reservoir, may be mounted an electric heating element 20 for use in case a fusible polish is to be used, such as solid wax. This heating element may advantageously be controlled by a thermostatic switch (not shown).

Near the bottom of the housing 17 are openings 21, through which air may pass to a central space surrounded by the annular brush 10. Corresponding openings 22 in the housing 11 and 23 in the central shield 24 are also provided for passage of the air drawn in through the openings 21.

The central shield 24 is preferably provided to enclose a space within the annular brush 10, so that the wax, or other polishing material may be distributed over the floor or other surface without any substantial part of it being applied directly to the bristles of the brush 10. The weight of the device may, if desired, be carried upon this central shield, as shown in the drawing, thus relieving the bristles of the brush from the full weight of the machine.

In the embodiment illustrated in Fig. 1, I have shown a fan 25 mounted upon the end of the motor shaft 14, which serves the dual purpose of promoting circulation of the air entering through the openings 21 and of spraying the liquid polishing material which

flows from the opening 19 through the tube 26. An annular felt strip 27 may also be provided to further assist in spreading the wax, or other polish, before it comes under the brush 10.

In the operation of the device which is described, the liquid, or fusible polishing material, is filled into the reservoir through the opening 18. If a fusible material is used, the heater 20 is preferably turned on, although if the material is previously fused and it is poured into the reservoir in a liquid condition, the heat of the motor may be sufficient to maintain it in liquid condition.

The motor is then started and the valve 29 is opened sufficiently to permit the desired amount of polishing material to flow through the tube 26. The liquid polish, as it drops from the tube 26 is struck by the rapidly rotating blades of the fan 25, and is converted thereby into a fine mist or spray, which is blown by the action of the fan against the surface which is being polished. The guard 24 prevents any of the polish which may be thrown from the tips of the blades from getting directly onto the brush 10, and allows it, instead, to drop down adjacent the felt 27, where it will be spread by the felt before coming under the brush 10. As a matter of practice, however, substantially the entire amount of wax fed will be deposited upon the floor, or other surface, in finely divided condition and such small amount of the wax as may strike the shield is ordinarily dried or solidified, so that no drip to the floor will result. This dried or solidified wax can easily be broken off from this shield when it collects to a degree which would be objectionable. As the polisher is moved over the surface, the portion of the surface which has had the wax applied thereto in the manner just described, comes under the brush 10, and the wax is rubbed thereby into the surface, and the surface is thoroughly buffed before finally being left by the further passage of the polishing device.

It is an advantage of the device as illustrated that any tendency of the brush to throw loose wax by centrifugal action serves only to throw the wax further into the brush, where it will be subsequently rubbed onto the surface, and there is no tendency whatever to throw such loose wax away from the brush. Furthermore, and particularly when the annular felt strip 27 is omitted or does not fully contact with the floor. The centrifugal action of the brush 10 serves to permit a circulation of air in through the openings 21, and out through the brush 10. This circulation makes for rapid drying of the wax, particularly when an emulsion or solution in a relatively slow drying liquid is used.

Another very important and related advantage of my invention is that wax, whether melted, in emulsion or in solution, may be

solidified by cooling or drying almost immediately after it is deposited or spread upon the surface which it is to be polished. Thus, by regulating the circulation of air according to the rate of feed of the wax or other polish and to the temperature or amount of liquid of the polishing material, my invention makes possible the solidifying of the film of polish before, or substantially as it comes under the polishing brush. Furthermore, any of the polish which may still remain in a gummy condition will reach first the inner periphery of the annular brush, and will thus be spread and dried before it can reach the outer periphery where the final buffing is given to the polish. Thus all streaking is avoided and I am able to prevent objectionable gumming of the polishing brush and it becomes possible to operate the device continuously without the necessity for changing from a spreading brush to a polishing brush. The polishing can thus be done in a single operation, instead of in two or more operations, as heretofore. In referring above, and in the accompanying claims, to a "film" of the polish, it is not intended to necessarily imply a continuous film, since the particles deposited upon the surface need not actually coalesce to form a continuous film. I have used this word rather to designate a very thin coating, whether in the form of discrete particles or actually as a continuous film, over the surface.

It is also an important advantage of this apparatus that there need be no pads or other devices saturated with wax, which will become hard and more or less useless upon drying. I do not, however, intend to limit my invention to the particular embodiment illustrated in Fig. 1.

In Figs. 2 and 3, I have shown another example illustrative of numerous spreading devices which may be used according to my invention. In these figures, I have illustrated a rotary air compressor having a circular housing 50, and inlet 51 and an outlet 52, and having within the housing 50 an eccentrically mounted rotor secured upon the shaft 14. This rotor carries a spring pressed wiping member 54, which serves to maintain a substantially pressure-tight contact with the inner wall of the housing 50, so that, upon rotation of the rotor 53, air will be drawn in behind the member 54 from the opening 51 during one rotation, and upon the following rotation will be driven before the member 54 out through the outlet 52. In this embodiment, the tube 26 for delivery of the polishing material is brought to the edge of the outlet tube 52, so that the stream of air which is blown across the end of the tube 26 will serve to atomize the polish and to blow it against the surface to be polished. It will be understood, of course, that the rotary compressor

is shown merely as one example and any other type of blower or compressor may be used.

Although I prefer to use the central guard 24 and its felt pad 27 to support the motor and frame, as shown in the drawing, this is in no way essential to my invention, and in some cases I have found it preferable to terminate the central guard 24 a short distance above the ends of the bristles of the brush 10. With this arrangement, the bristles of the polishing brush will act as centrifugal impellers to effect circulation of air through the brush, and therefore to draw air under the edge of the central guard 24 and along the surface where the wax has been, or is being spread. Thus rapid drying of the wax or other polishing material may be promoted, and gumming of the polishing part of the brush may be substantially prevented.

Many other changes and modifications may be made within the scope of my invention, and many other polishing materials than those specifically mentioned, and the device may be used upon many different types of surfaces, including, for example, automobiles and furniture, as well as floors, and may advantageously be made in varying sizes according to the requirements of the particular use to which it is to be put. Where, as in the case of automobiles, etc., the polisher is to be used upon steel or iron surfaces, it may advantageously be combined with an electromagnet adapted to save the operator from some of the necessity for pressing the device against the surface, when used on other than horizontal surfaces.

What I claim is:

1. A waxing and polishing device which comprises, a polishing means having an enclosed space whereby when the device is used the polishing means surrounds an unobstructed area upon which wax is to be distributed, a liquid reservoir, means for distributing liquid wax from the reservoir in a comminuted form on and confining it to a substantial portion of the unobstructed area whereby that portion of the polishing means defining the enclosing space is maintained out of contact with the material being distributed until after the material has contact with the surface to be polished, means for moving said polishing means relative to said device as a whole, the said device being movable bodily over the surface to be polished whereby the polishing area will gradually encroach upon the distributing area.

2. A waxing and polishing device as defined in claim 1 which further includes a heater for melting the wax in said reservoir.

3. A waxing and polishing device as defined in claim 1 which further includes means for circulating air over that portion of the surface upon which wax is distributed.

4. A waxing and polishing device which

comprises, a polishing means having an enclosed space whereby when the device is used the polishing means surrounds an unobstructed area upon which polish is to be distributed, a liquid reservoir, means for depositing liquid wax from the reservoir in a comminuted form on and confining it to a substantial portion of the unobstructed area, which means includes a guard interposed between the polishing means and the means for distributing liquid wax, whereby the polishing means defining the enclosed space is maintained out of contact with the material being deposited, and means for moving said polishing means relative to said device as a whole, the said device being movable bodily over the surface to be polished whereby the polishing area will gradually encroach upon the distributing area.

5. A waxing and polishing device which comprises, a polishing means having an enclosed space whereby when the device is used the polishing means surrounds an unobstructed area upon which wax is to be distributed, a liquid reservoir, a heater for heating the wax in the reservoir, means for distributing wax from the reservoir in a comminuted form on and confining it to a substantial portion of the unobstructed area, which means includes an outlet conduit from the reservoir, a rotatable member for comminuting the wax and for creating an air blast and a guard interposed between the member and the polishing means, and means for moving said polishing means relative to said device as a whole, the said device being movable bodily over the surface to be polished whereby the polishing area will gradually encroach upon the distributing area.

Signed at New York, New York, this 25th day of May, 1931.
